(57) **CLAIM**

The ornamental design for a display screen or portion thereof with a graphical user interface for analyzing and presenting drilling data, as shown and described.

DESCRIPTION

FIG. 1 is a front view of a first image of a display screen or portion thereof with a graphical user interface for analyzing and presenting drilling data according to a first embodiment thereof;

FIG. 2 is a front view of a second image of a display screen or portion thereof with a graphical user interface for analyzing and presenting drilling data according to a first embodiment thereof;

FIG. 3 is a front view of a third image of a display screen or portion thereof with a graphical user interface for analyzing and presenting drilling data according to a first embodiment thereof;

FIG. 4 is a front view of a display screen or portion thereof with a graphical user interface for analyzing and presenting drilling data according to a second embodiment thereof; and, FIG. 5 is a front view of a display screen or portion thereof with a graphical user interface for analyzing and presenting drilling data according to a third embodiment.

The broken line portions of the figure drawings is included to show unclaimed subject matter only and forms no part of the claimed design. The appearance of the transitional image sequentially transitions between images shown in FIGS. 1-3. The process or period in which one image transition s to another image forms no part of the claimed design. The graphical user interface shown in FIGS. 1-3 include optimal operating parameter ranges and set points that transition between the images shown in FIGS. 1-3.

FIG. 1

FIG. 2

FIG. 3

FIG. 4

FIG. 5
